SPARK PLUG TESTER

William Borchert and Fred L. Borchert,
Rockford, Ill.

Application January 9, 1933, Serial No. 650,774

6 Claims. (Cl. 175—183)

This invention relates to testing machines, and more specifically to mechanism for testing the firing capacity of spark plugs.

There has been known heretofore certain mechanisms designed to accomplish this purpose, but all of them have been open to more or less serious objection. In some of these machines a single large compression chamber has been employed having a series of threaded openings each designed to accommodate a different size of plug. In this construction it was necessary to screw the plug into the threaded opening with sufficient tightness to prevent the escape of gas under the pressure used for testing. This necessitated the use of a wrench which frequently slips off the nut, breaking the porcelain of adjacent plugs. Furthermore, the tester is frequently used on the top of a glass show case, and the use of a heavy wrench in tightening the plugs commonly results in the breaking of the glass of the case. Another objection to this type of construction lies in the fact that different sizes of holes are required to accommodate the different sizes of spark plugs in common use. This means that it is necessary to plug all of the holes except the one in use, and, consequently, it usually requires the removal of one plug before the plug to be tested can be inserted. Sometimes it also involves the insertion of a plug in a hole employed for a previous test. This construction also involves the difficulty in keeping all of the holes air-tight to prevent the loss of pressure in the compression chamber. In many of the prior art constructions air has been provided to the compression chamber from the usual air tanks of garages and the like, the air being supplied under pressure. The objection to this arrangement lies in the fact that it requires a permanent connection between the testing mechanism and the air line so that the testing mechanism is either fixed in place or movable only through a relatively small area, depending on whether the connection was made by means of pipes or flexible tubes. Furthermore, since the advent of low pressure tires, the air pressure carried in the usual tanks is too low for satisfactory operation of the testing mechanism which requires that the tanks be held at a considerably higher pressure than would otherwise be desirable.

A primary object of the invention is the provision of a self-contained testing unit which may be moved from place to place as the occasion demands, and requires no permanent or fixed connection.

Another object of the invention is to provide

a spark plug tester having improved means for positioning the plugs in a testing position.

We have also aimed to provide a construction having means for positioning plugs of different sizes in the same opening to the compression chamber.

A further object is to provide mechanism wherein handles and plug positioning mechanism operate in a substantially horizontal plane.

A still further object is the provision of pump mechanism such that the power required to move the handles is substantially the same throughout its stroke to provide uniform and smooth operation.

Other objects and attendant advantages will become apparent to those skilled in the art from the following description and the accompanying drawings in which—

Figure 1 is a side view of the tester showing the upper portion in elevation and the base in section;

Fig. 2 is a section on the line 2—2 of Figure 1;

Fig. 3 is a fragmentary top view of the battery holding means and bottom panel;

Fig. 4 is a section on the line 4—4 of Figure 1;

Fig. 5 is a vertical section taken longitudinally through the upper portion of the tester;

Fig. 6 is a fragmentary side view of the cradle for holding the spark plug;

Fig. 7 is a section on the line 7—7 of Fig. 5;

Fig. 8 is a section on the line 8—8 of Fig. 5;

Fig. 9 is a section on the line 9—9 of Figure 1;

Fig. 10 is a section substantially on the line 10—10 of Figure 1;

Fig. 11 is a fragmentary side view of a preferred embodiment of the invention;

Fig. 12 is a vertical section through the housing of the form shown in Fig. 11 showing the contents in elevation, and

Fig. 13 is a fragmentary view showing the wiring connections of the preferred form.

The invention contemplates a construction having a compression chamber and pump mechanism for developing air pressure within the compression chamber. Means are provided for indicating the pressure in the chamber. Likewise, relief mechanism is provided for relieving excessive pressure in the chamber, such as that which might be caused by an explosion therein. Novel means are provided for inserting the spark plug so that the spark gap rests within the compression chamber, and for holding the plug in this position. In order to pass a spark across the spark gap of the plug to test the same, means are provided for producing such a spark from dry

50

55

cell batteries. The entire mechanism is so arranged as to constitute a testing unit, and the parts are so assembled as to give certain improved and beneficial results, a portion of which results 5 are obtained solely through the space relationship of the parts.

Referring first to Figure 1, a housing 11 is arranged to act as a base having a hollow interior 12 for the reception and support of electrical 10 means presently to be more fully described. Feet 13 are fastened to the bottom side of the housing by means of screws 14, and may advantageously be of rubber or other resilient material to provide a cushion support for the tester. A body, 15 designated generally by the numeral 15, is secured to the top of the housing 11 by means of screws 16 or by other suitable means. In the present instance this consists of a platform 17 having a rearwardly extending arm 18 and an 20 upwardly extending cylinder and chamber portion 19 which are cast integral in the form of a single piece. Formed in the body portion 19 is a compression chamber 21 and a cylinder 22 connected by means of a passageway 23 so that air 25 may be passed from the cylinder into the compression chamber. A cylinder head 24 is positioned over the front end of the cylinder 22 by means of cap screws 25. The chamber 21 is formed with openings on both the front and rear 30 side of the portion 19. A bore 26 concentric with and somewhat larger than the chamber 21 is formed at the forward end of the chamber to receive an observation window 27. The window 27 is secured in the bore 26 by means of a ring 35 of rubber or other resilient material. This ring consists of a U-shaped circular piece of rubber having a portion 28 arranged to bear against the marginal edge of the window 27 and flanged portions 29 and 31 arranged to bear against the 40 opposed sides of the window adjacent its periphery so as to provide a resilient mounting for the window. A retaining ring 32 is secured against the body 15 by means of screws 33, and bears against the rubber ring to compress the ring and 45 hold the window tightly against the body. In this instance we have shown the window 27 as being of plate glass, but it may be made of any suitable transparent material, one such material being so-called shatter-proof or laminated 50 glass. The walls of the chamber 21 are provided with an outlet 34 for the threaded reception of a pressure gauge 35 of conventional design, the gauge being arranged to indicate the pressure in the chamber and calibrated to a suitable scale. 55 The chamber 21 is also provided with an opening 36 arranged for the threaded reception of a relief valve 37 which may advantageously be of the type having a ball valve member 38 held in position against a suitable seat by means of a 60 spring 39. This relief valve may be made to serve one or a combination of functions, depending upon the desires of the manufacturer. For example, it may be set to open at the predetermined pressure at which the test is to be carried 65 on so that when air is injected into the compression chamber it will automatically open when the desired pressure is attained and thus automatically limit the pressure to the testing pressure. Under these circumstances, it will be seen that 70 should an explosion occur in the compression chamber, which might conceivably occur should a plug be inserted therein covered with gasoline or other explosive fuel, the excessive pressure thus developed in the chamber would be relieved 75 through the valve. On the other hand, the pres-

sure gauge 35 may be relied upon solely for the purpose of indicating the testing pressure and the relief valve set to open at a higher pressure to provide the necessary safety and thus insure against the effects of an accidental explosion. 5

The body portion 19 is also provided with a bore 41 at the rear opening of the compression chamber 21 and concentric therewith for the reception of a gasket 42 of resilient material, preferably of rubber. The gasket is held in the bore by means of a circular retainer 43 secured to the body by means of screws 44. The retainer 43 is of such diameter as to contact only the outer periphery of the gasket to leave sufficient space for contact of the flange of a spark plug. Likewise, the inside diameter of the gasket is such as to receive the threaded portions of the spark plug within relatively close limits. Thus, through this arrangement the conventional spark plug, such as shown at 44 of the type commonly employed in automotive engines, may be inserted into the compression chamber with the threaded portion of the plug foremost, as shown in Fig. 5 until the flange 45 of the plug comes into contact with the bushing 42. The flange is forced against 20 the bushing with sufficient pressure to prevent the escape of air therebetween. In this manner the spark gap 46 of the plug is positioned within the compression chamber so that the performance of the plug under pressure may be observed through the window 27. Since spark plugs for automotive use vary to a certain degree in size, that is, the diameter of the threaded portion of the plug, the internal diameter of the gasket 42 is made of such size as to closely receive the larger of these plugs. In order to prepare the smaller sizes to be similarly tested by means of the same devices, a bushing 47 is provided and is threaded on its inner surface for reception on the threaded portion of the spark 30 plug, as shown in Fig. 8. This bushing is of such size as to bring the threaded portion of the smaller plugs to the same apparent diameter as the larger plug. It will be seen that any number of these bushings may be provided to accommodate any smaller size of plug to the testing mechanism. The threads on the inner side of the bushing are so made that the bushing may be turned onto and off from the plug solely by means of the fingers, so that the testing operations are not materially retarded by the necessity for using the bushing. 40

In order to position a spark plug with the spark gap in the compression chamber and the flange firmly against the gasket, a cradle 48 is employed having a notched upper surface 49 and reinforcing 51. The forward side of the cradle is provided with a face 52 arranged to be brought against the metal portion or nut 53 of the plug. Thus, when the cradle is moved forward, the surface 52 of the cradle bears against the nut 53 of the plug forcing the plug into the compression chamber and the flange 45 firmly against the gasket 42. The cradle 48 is pivotally supported through arms 54 and 55 to a yoke comprising yoke members 56 and 57, the arms 54 and 55 carrying pivots 58 and 59 journaled in the yoke members. The yoke members 56 and 57 are in turn journaled at their lower ends on screws 61 and 62 in opposite sides of the body 15, and are held together at their upper ends by means of a pin 63. The pin 63 also has journaled thereon a latch member 64, the latch member having ears 65 for the reception of the pin 63. A coiled spring 66 is wound about the 50 60 70 75 80 85 90 95 100 105 110 115 120 125 130 135 140 145 150 155 160 165 170 175 180 185 190 195 200 205 210 215 220 225 230 235 240 245 250 255 260 265 pin 63 between the yoke members 56 and 57 and also between the ears 65 of the latch, and acts between the yoke members and the latch to urge the same in a counter-clockwise direction facing Fig. 5. A shaft 67 is journaled in the yoke members 56 and 57 and supports a spur gear 68 fixedly secured on the shaft between the two yoke members and in a position to be engaged by the latch member 64. A hand wheel 69 is mounted 10 on the outer end of the shaft 67 to permit manual rotation of the shaft and the spur gear 68. The spur gear 68 is arranged to cooperate with gear teeth 71 on the top of the body portion 19 so that upon rotation of the hand wheel 69 the yoke will 15 be rotated about the screws 61 and 62.

Thus, to position the spark plug 44 in a testing position with respect to the compression chamber, the yoke is rotated in a clockwise direction facing Fig. 5 until it is possible to insert 20 the plug 44 with the fingers into the compression chamber. This will ordinarily necessitate complete disengagement of the spur gear 68 and the teeth 71. When the plug is thus positioned, the yoke is rotated in a counter-clockwise direction and the cradle 48 is guided against the nut 53 of the plug. This operation may be carried out by simply grasping the yoke members 25 and swinging the yoke. During this movement the spur gear 68 will ride onto the teeth 71. In order to finally tighten the plug into its socket, 30 the operator grasps the hand wheel 69 and rotates it, bringing the flange 45 of the plug snugly against the gasket 42. As the hand wheel is rotated, the latch 64 clicks along the spur gear so that when the hand wheel is released the latch 35 prevents backward movement of the gear, thus holding the plug firmly in the tightened position. To release the plug, the latch 64 is moved in a clockwise direction facing Fig. 5, thus releasing the spur gear in which position the yoke 40 may be rotated to the aforementioned position in which the plug may be removed. The yoke is thus rotatable from an inoperative position in which the plug may be inserted into the compression chamber, and an operative position in 45 which the plug is firmly held in its testing position within the chamber.

The piston 72 is positioned in the cylinder 22 for reciprocation to compress the air in the compression chamber. A leather or other cup 73 is positioned at the front end of the piston and is secured thereto by means of a nut 74 threaded to a rod 75 on the front end of the piston. The nut 74 is of sufficient width to completely fill the space between the flange sides of the cup and extend slightly beyond these ends so that when the piston reaches the forward end of its stroke, substantially all of the air in the cylinder is displaced. A spring ring 76 acts against the flange 50 sides of the cup to maintain them in close proximity to the walls of the cylinder.

Referring now more particularly to Figs. 9 and 10, the piston is arranged to be reciprocated in the cylinder by means of handles 77 and 78. These handles are pivotally supported intermediate their ends on the arm 18 by means of bolts 79 and 81. The handles extend slightly beyond the pivotal points and terminate in intermeshing gear teeth 82 and 83. Through this 55 arrangement reciprocation of one of the handles brings about a corresponding movement of the other handle which insures uniform action on the piston. The handles are slotted intermediate their ends, as shown at 84 and 85 for the reception of links 86 and 87 which are pivotally

secured to the handles by means of pins 88 and 89 extending across the slots. The forward ends of the links 86 and 87 are pivotally supported in a slot 91 in the rear end of the piston 72 by means of a threaded pin 92. The links are curved, as shown at 93, so as to pass into the cylinder to move the piston to the front extremity of the cylinder. 5

Thus, upon movement of the handles 77 and 78 toward and away from each other, the piston 72 10 is reciprocated in the cylinder 22, drawing air into the cylinder through an opening 94 in the cylinder wall and forcing the air into the compression chamber 21 through the passageway 23. A valve 90 is positioned in the passageway 15 23 and is arranged to be opened when pressure is applied to the end adjacent to the cylinder 22 to permit the passage of air from the cylinder into the compression chamber and to be closed when this pressure is relieved to prevent the return flow of air. This valve may advantageously be of the type usually employed in automobile tires and commonly called a Schrader valve. 20

Electrical energy for causing a spark to pass across the spark gap of the plug during the testing operations is provided by a secondary vibratory type induction coil and dry cell batteries positioned in the housing 11. The induction coil, indicated generally by the numeral 95, is connected to the center conductor 96 of the plug through 25 a lead 97 having a spring-operated clip 98 for convenient attachment to the plug. The coil 95 is provided with conventional vibratory mechanism 99 and is provided with electrical energy from batteries 101, 102, 103 and 104, the flow of 30 electrical energy being controlled by a push button switch 105 positioned in the top side of the housing 11 in a position to be normally guarded against accidental actuation when the handles occupy their normal position shown in dotted 35 lines in Fig. 9. Novel means are employed for holding the batteries and for making the proper battery connections. The coil 95 and batteries are supported upon a bottom panel 106 secured to the housing 11 by means of screws 107. Positioned upon the bottom panel 106 are spaced parallel vertical panels 108, 109 and 111, the vertical 40 panels being spaced a distance slightly greater than the diameter of the batteries. A longitudinal panel 112 extends between the vertical panels 45 and provides a series of four chambers for reception of the batteries. A top panel 113 is affixed to the top end of the panels 108-112, the distance 50 between the top panel 113 and the bottom panel 106 being just sufficient for the reception of the battery inclusive of the upstanding central terminal 114 thereof. Grooves 115 and 116 in the bottom panel serve to receive the upstanding terminals of the batteries 102 and 103 so that 55 these batteries may only be inserted into their respective chambers with the central terminal downward. Likewise the upper plate 113 is provided with grooves 117 for the reception of the central terminals of the batteries 101 and 104 so that these may only be inserted with the terminals 60 on the upper end. This device insures that the batteries will always be inserted in the proper manner and prevents them from at any time being accidentally improperly connected. A spring 65 contact member 118 serves to connect the central terminal of the battery 104 with the bottom or outer terminal of the battery 102, while the contact member 119 connects the outer terminal of the battery 103 to the switch 105. Likewise the contact member 121 connects the central ter- 70

75

5 minal of the battery 101 to the primary of the coil 95. Likewise spring contact members 122 and 123 on the bottom panel 106 serve to connect opposite terminals of the batteries 101 and 102, and 10 103 and 104, respectively, to complete the circuit. The switch 105 is also connected to ground by means of a lead 124 whereby closing of the switch 105 completes the circuit through the primary of the coil, one lead of the primary of the coil being 15 grounded by means of a lead 125. In order to facilitate the insertion and removal of the batteries from their closely confined positions, strips of cloth or similar suitable material 126 and 127 are secured to the vertical panel 109 by means of 20 screws 128 and 129 and are of sufficient length to loop into adjacent chambers, as best shown in Fig. 2. Thus the battery is inserted with the pieces of cloth or tabs looped around them so that by pulling the ends of the tabs the batteries 25 may be slid out of their operative positions.

While the means shown in Figs. 1-3, inclusive, for supplying electrical energy to the plug under test is of advantage where it is desired to have a completely portable testing machine, we have 25 shown in Figs. 11-13 a preferred electrical system, which, while less completely portable than the form first above mentioned, is sufficiently portable to normally accomplish the purpose. In this form a secondary vibratory induction coil 30 131 is secured to the bottom panel 106 by means of a strap 132, this coil having the usual vibratory elements 133. One terminal of the secondary winding of the coil is connected to the spark plug through the lead 97, the other terminal of 35 the secondary winding being grounded. A conventional step-down transformer 134 is also secured to the bottom panel 106 within the housing 11 and is connected with the primary of the induction coil 131. The transformer 134 is connected 40 to a conventional power receptacle 135 secured in the side of the housing 11, one of the leads between the receptacle and the transformer passing through a manually controlled switch 136. Thus, when the receptacle 135 is connected 45 to a commercial light circuit such as the usual 110 or 220 volt circuits, power will be supplied to the transformer when the switch 136 is closed. The voltage of the commercial power will be stepped down in the transformer to six volts and then 50 supplied to the induction coil 131. It should be understood, of course, that the transformer will vary depending upon the voltage of the commercial power supply. The primary of the induction coil 131 is also connected to terminals 137 and 138 55 secured in the walls of the housing 11, the circuit passing through the switch 105 as previously described. The terminals 137 and 138 serve for the connection of the conventional six volt storage battery, so that upon the closing of the 60 switch 105, current will be supplied to the induction coil 131 from this source of current. Thus, in the preferred form just described, the electrical energy may be taken from either a conventional storage battery or from a commercial 65 lighting circuit, depending upon the convenience of these different sources of energy. In this manner the cost of operating the tester will be considerably lower than when the same is operated through the use of dry cell batteries of the 70 type shown in Figs. 1-3.

The advantage of our improved construction will doubtless have become apparent. It will be seen that the device presents a self-contained unit and does not require attachment to a supply 75 of gas or air nor to a supply of electrical energy.

The pressure in the compression chamber is developed by means of a pump operated through horizontally movable handles, the handles being horizontally movable in their pumping stroke. No strain has set up through their operation and, 5 consequently, the device may be used on the glass showcase of spark plug sales establishments without danger of breaking the glass during pumping operation. Furthermore, when the handles are moved into a parallel position represented 10 by the completion of the power stroke of the piston, the handles occupy a position such as to protect the switch mechanism from being accidentally actuated. The plug is inserted in the tester entirely without the use of wrenches or 15 other extraneous positioning means merely through the operation of the yoke, so that there is no danger of showcases or the porcelains of adjacent plugs being broken. Furthermore, the plug is inserted longitudinally into the chamber 20 and is not screwed in in the conventional manner which materially increases the speed with which the test may be conducted, since only an instant's time is required for the satisfactory insertion of the plug or the removal thereof. Furthermore, 25 all sizes of plugs are tested by insertion in the same hole which renders the mechanism much more simple than has heretofore been possible. Means are provided for relieving any extreme pressure which may be developed in the compression chamber, thereby avoiding the danger which might result from breakage of the window. We have also provided improved means for 30 mounting and securing the window in the testing mechanism, and means for accurately gauging the pressure under which the test is conducted. Another advantage in the construction lies in the fact that the common Schrader valve 35 is employed for preventing return flow of air from the compression chamber to the pump. 40

A novel feature of the invention is the manner of supporting and retaining the batteries and the means for removing the same from their support, the means being so constructed that the batteries cannot be inserted in an improper 45 manner.

Attention is also directed to the fact that we have provided means whereby the electrical energy for operating the tester may be obtained from either the conventional six volt storage 50 battery or commercial lighting circuits. In the former case the terminals of the battery are connected directly to the induction coil, whereas when the commercial lighting circuit is employed, the current is first passed through a step-down 55 transformer from which it is supplied to the induction coil at the desired voltage of six volts. Independent switch means are provided for use with the two circuits.

While we have thus described and illustrated a specific embodiment of our invention, we are aware that numerous alterations and changes might be made therein without materially departing from the spirit of the invention and the scope of the appended claims, in which— 65

We claim:

1. In a spark plug tester, a compression chamber having an open end, a compressible gasket positioned in the chamber wall at said open end, and rack and pinion means for pressing a flange 70 of a spark plug firmly against said gasket when the threaded end of the plug is inserted in said chamber to provide a substantially air-tight junction between the flange and the gasket.

2. In a spark plug tester, the combination of a 75

- compression chamber having an open end of such diameter as to permit the longitudinal insertion of the threaded end of a spark plug, a resilient gasket positioned in the walls of said chamber, 5 means for normally maintaining the gasket in position, means adapted to bear against the nut of the plug movable toward and away from said open end for inserting and for applying longitudinal pressure to said spark plug to force the 10 flange thereof firmly against the gasket to provide a substantially air-tight junction therebetween and a rack and pinion for moving said last mentioned means for quick insertion of plugs of variable size.
- 15 3. In a spark plug tester, the combination of a compression chamber having an open end of such diameter as to permit the longitudinal insertion of the threaded end of a spark plug, a gasket in the walls of said chamber surrounding said opening, cradle mechanism arranged to bear against the nut of the plug and a rack and pinion mechanism for actuating the cradle to press the flange thereof firmly against the gasket and provide an air-tight junction therebetween.
- 20 4. In a spark plug tester, a compression chamber having an open end on a compressible gasket positioned in the chamber wall at the open end, rack and pinion means for pressing a flange of the spark plug against said gasket when the 25 threaded end of the plug is inserted in said chamber, and manually operable means for turning the pinion to tighten the plug in position to provide a substantially air-tight junction between the flange and the gasket.
- 25 5. The combination in a spark plug tester of a hollow base carrying electrical supply means, a compression chamber and a pump chamber supported on the base in superimposed relationship, the compression chamber having a window defining the front thereof and an opening at the 30 rear for the reception of a spark plug, said pump chamber also having a rear opening, a piston in the pump chamber, a pair of horizontally disposed handles positioned on either side of the pump chamber for actuation from the front toward and away from the pump chamber to actuate the piston through the rear opening of the pump chamber, a yoke pivoted on the pump chamber spanning the compression chamber for securing the spark plug in the opening thereof, 10 and rack and pinion mechanism between the yoke and the top of the compression chamber for tightening and releasing the plug.
- 35 6. The combination in a spark plug tester of a hollow base carrying electrical supply means, a compression chamber and a pump chamber supported on the base in superimposed relationship, the compression chamber having a window defining the front thereof and an opening at the rear for the reception of a spark plug, said pump 20 chamber also having a rear opening, a piston in the pump chamber, a pair of horizontally disposed handles positioned on either side of the pump chamber for actuation from the front toward and away from the pump chamber to 25 actuate the piston through the rear opening of the pump chamber, a yoke having a pair of arms pivoted on the pump chamber, the yoke spanning the compression chamber, a cradle connecting the arms and pivotally supported thereon adapted to contact the nut of a plug to tighten and release the plug in the opening of the compression chamber upon pivotal movement of the yoke, a rack above the compression chamber, and a manually rotatable pinion on the yoke 30 cooperable with the rack for the purpose of tightening the plug in the compression chamber and releasing the plug while under pressure.
